UNITED STATES PATENT OFFICE.

OSCAR A. JOHNSON, OF MARQUETTE, MICHIGAN.

METAL-BARREL COVER.

1,183,206.

Specification of Letters Patent. Patented May 16, 1916.

Application filed April 16, 1915. Serial No. 21,725.

To all whom it may concern:

Be it known that I, OSCAR A. JOHNSON, a citizen of the United States, residing at Marquette, in the county of Marquette, 5 State of Michigan, have invented certain new and useful Improvements in Metal-Barrel Covers; and I do hereby declare the following to be a full, clear, and exact description of the invention, such as will enable others skilled in the art to which it 10 appertains to make and use the same.

This invention relates to improvements in barrels and particularly to heads for metal barrels.

15 One object of the invention is to provide a novelly constructed barrel and head, the latter of which can be effectively locked against removal.

20 Other objects and advantages will be apparent from the following description when taken in connection with the accompanying drawing; in which:

Figure 1 is a plan view of one end of a barrel made in accordance with my invention, Fig. 2 is a transverse section on the line 2—2 of Fig. 1, Fig. 3 is an enlarged transverse sectional view on the line 3—3 of Fig. 1, and Fig. 4 is an enlarged vertical section on the line 4—4 of Fig. 2.

25 Referring particularly to the accompanying drawing, 10 represents the upper end of a sheet metal barrel, the same being bent downwardly within the barrel and then upwardly, as shown respectively at 11 and 12.

30 A cover or head 13 has its peripheral edge formed with a downturned flange 14 in which are formed the inclined slots 15, the same opening through the lower edge of the flange. Disposed between the downwardly

35 and upwardly extending portions of the top of the barrel, at regularly spaced points are pins 16, the ends of which are reduced as at

17, and passed through suitable openings in said downturned and upturned portions, the ends of said pins which project beyond said 45 portions of the top of the barrel having suitable nuts or washers 18 secured thereon.

On the intermediate portion of each of the pins is mounted a sleeve 19 to provide rolling contact with the inclined walls of the 50 slots 15, the same opening through the lower edge of the flange.

At several diametrically opposite points on the head 13 are vertically extending lugs 20, the same extending radially and being 55 arranged to be received in the bifurcations 21 of the pivoted latches 22 mounted on the upper edge of the barrel.

The latches and the lugs are apertured so as to receive the wire of a seal therethrough 60 to lock the same against being opened. If desired, suitable pins or like devices may be passed through the other latches and lugs.

What is claimed is:

A metal barrel comprising a surrounding 65 wall, the upper portion of which extends downwardly and upwardly within the barrel, transverse pins disposed between the downwardly and upwardly extending portions, a cover having a depending flange for 70 disposition between said downwardly and upwardly extending portions and having inclined slots for the reception of said pins, apertured lugs carried by the cover and an apertured pivoted latch member carried by 75 the barrel for interlocking engagement with the said lug to receive a securing device therethrough.

In testimony whereof, I affix my signature, in the presence of two witnesses.

OSCAR A. JOHNSON.
